Matthew Kelley.

UNITED STATES PATENT OFFICE.

HERBERT J. Gwyer, of New York, N. Y.

REFRIGERATOR-DRAIN.

1,206,840.

Specification of Letters Patent.

Patented Dec. 5, 1916.

Application filed November 19, 1915. Serial No. 62,283.

To all whom it may concern:

Be it known that I, HERBERT J. Gwyer, a citizen of the United States of America, residing at New York city, New York, have invented a new and useful Refrigerator-Drain, of which the following is a specification.

My invention relates to improvement in refrigerator construction and the object of the present invention is to provide an improved drain outlet which is economical, simple, durable, and which may be readily cleaned and which will furthermore operate to prevent air from entering the refrigerator via said outlet.

In the accompanying drawing: Figure 1 is a front elevation illustrating a refrigerator of conventional form and provided with my improvement. Fig. 2 is a relatively enlarged sectional view of details. Fig. 3 is a plan view of a detached detail.

1 represents a refrigerator casing of suitable form. In this instance the ice chest is located at the upper part 2 of the casing.

25 3—4 are telescopic sections of a drain pipe by which the water from the upper part of the refrigerator, due to melting ice, is conveyed to the drain outlet.

5 is the outlet end of the drain pipe at 30 the bottom of the refrigerator. This outlet end 5 is trapped by means of a bell-shaped trap 6 which partially overstands the upper end of the pipe 5 and projects into a channel around said upper end as shown in Fig. 2. This trap bell 6 is carried by a perforated plate 7 preferably provided with a flange 8 with which flange the lower section 4 of the telescopic pipe engages, as best seen in Fig. 2, so that said parts mutually steady one another, also, so as to prevent leakage.

45 5^a is an annular wall projecting outwardly and upwardly from the pipe 5 near to but below its upper end. The inner surface of this wall is threaded.

9 is an annular member having a flange 10. The side wall of this annular member below the flange 10 is threaded to fit into the threaded part of the wall 5^a while the 50 flange 10 overstands the upper edge of said wall.

11 is the interior lining of the refrigerator. This lining is perforated in line with the drain pipe 4 to receive the outlet pipe 5 and the associated parts. The edge of the

opening in the lining 11 is depressed approximately to the thickness of the flange 10, so that when the annulus 9 is screwed into the wall 5^a, the flange 10 will operate as a nut to tightly clamp down upon the 60 lining 11 and hold the parts assembled as shown in Fig. 2. The inner edge of the ring 9 may also have a depressed seat as shown in Fig. 2 for supporting the plate 7 and bell 6 thus holding the parts in the 65 proper position whereby when all the parts are assembled ready for use they will be firmly held against accidental displacement. As the ice melts in the upper part 2 of the refrigerator, the water will run down the 70 pipe 3—4 and through the perforations in the plate 7 until the channel around the upper end of the outlet pipe 5 is filled to the level of said upper end, and thereafter as the water continues to run down the pipe 75 sections 3 and 4, it will be discharged through the pipe 5. By reason of the fact that the lower edge of the bell 6 projects into the water in the channel around the upper end of the pipe 5, it follows that air 80 cannot enter the chest through the drain pipe.

If it should be desired to clean the trap, the section 4 of the pipe may be lifted thereby unlocking the plate 7 which may 85 then be lifted bodily with the bell 6 thus affording easy access to the channel around pipe 5 and making it correspondingly easy to cleanse the plate 7. At such a time too, the inside of the lining 11 may be thoroughly cleaned, and since the flange 10 lies substantially flush with the inner surface of the lining 11, the water used to wash the interior of the refrigerator will run freely out through the discharge pipe. 95

What I claim is:

1. In a refrigerator, a bottom lining having a passage, an outlet pipe located in line with said passage, an annular wall projecting outwardly and upwardly from said outlet pipe from a point near to, but below the upper end thereof, to a point above the upper end thereof, with means for securing said annular wall to said lining around the opening therein, to form a water tight joint, 100 a bell trap overstanding the upper end of said outlet pipe, the lower edge of the bell extending below the upper end of said pipe and being free therefrom and from the surrounding wall, and means for suspending 110

said bell in said position, a drain pipe leading from above down to said outlet and communicating therewith above said bell, said bell suspending means having passages in line with said drain pipe to allow water to flow from the latter to the outlet pipe.

2. In a refrigerator, a bottom lining having a passage, an outlet pipe located in line with said passage, an annular wall projecting outwardly and upwardly from said outlet pipe from a point below the upper end thereof to a point above the upper end thereof, clamping means for securing said annular wall to said lining around the opening 15 therein to form a water-tight joint, a bell trap overstanding the upper end of said outlet pipe, the lower edge of said bell extending below the upper end of said pipe, but being free therefrom and from the surrounding wall, and means for suspending said bell in said position, said suspending means being mounted upon but independently removable from said clamping means, and a drain pipe leading from above down to said outlet and communicating therewith above said bell, said bell suspending means having passages in line with said drain pipe to allow water to flow from the latter to the outlet pipe.
3. In a refrigerator, a bottom lining having a passage, an outlet pipe located in line with said passage, an annular wall projecting outwardly and upwardly from said outlet pipe from a point below the upper end

thereof to a point above the upper end thereof, with means for securing said annular wall to said lining around the opening therein to form a water-tight joint, an annular recess in the upper part of said securing means around the opening therein, a 35 perforated plate removably mounted in said recess, a bell trap carried by said plate, the lower edge of the same extending down to and around the upper end of said outlet pipe and separated therefrom and from the 40 surrounding annular wall, said perforated plate having an upwardly projecting annular wall around the perforations therein, and a drain pipe fitting said annular wall.

4. In a refrigerator, a bottom lining having 50 a passage, an outlet pipe located in line with said passage, an annular wall projecting outwardly and upwardly from said outlet pipe from a point below the upper end thereof to a point above the upper end thereof, the inner surface of said annular wall near its upper end being threaded, an annular clamping member threaded on its outside to engage the threaded part of the annular wall, said annular member having an outwardly 55 projecting flange, whereby said annular wall and annular member may clamp said lining between them, a perforated plate supported on said annular member and a bell trap suspended from said perforated plate, said perforated plate being detachable from said annular member.

HERBERT J. GWYER.
